UNITED STATES PATENT OFFICE.

THEODORE F. W. SCHMIDT, OF DAYTON, OHIO, ASSIGNOR OF ONE-HALF TO
LAUBACH & IDDINGS, OF SAME PLACE.

PAPER-PAIL COVER.

SPECIFICATION forming part of Letters Patent No. 369,559, dated September 6, 1887.

Application filed July 23, 1887. Serial No. 245,108. (No model.)

To all whom it may concern:

Be it known that I, THEODORE F. W. SCHMIDT, of Dayton, in the county of Montgomery and State of Ohio, have invented certain new and useful Improvements in Paper-Pail Covers, of which the following is a specification.

The object of my invention is to provide a detachable cover for a paper bucket employing a bail, the bail holding the cover in position, and the cover in turn bracing and supporting the bail, thereby stiffening the bucket and making it more substantial.

The features of my invention will be explained in the description of the accompanying drawings, in which—

Figure 1 is a perspective view of my improvement attached to the bucket in position for use. Fig. 2 is a top plan view of my improved cover attached to an oval bucket. Fig. 3 is a sectional elevation showing the lid raised for folding the bail over to fill or empty the bucket.

1 represents an ordinary rectangular paper bucket.

2 represents the bail, which is hooked to the folds of the bucket in the usual manner.

3 represents my improved cover, which is a paper blank cut in the desired size and shape to cover the bucket. The dotted line 4 represents the edge of the bucket under the cover.

5 represents a semicircular slit pierced through the cover with the ends of the slit terminating with the outer sides of the bail-limbs.

The bail is readily inserted through the slit, and when the cover is brought down upon the bucket the bail serves to hold the cover in position. The part of the cover between the arms of the bail serves as a stiffener or support of the bail. This construction is very cheap, simple, easily applied and removed, and at the same time the parts are held in position for use.

Having described my invention, what I claim is—

1. In combination with a paper bucket and bail, the detachable cover 3, having the semicircular bail-slit 5, substantially as specified.

2. The paper-bucket cover 3, provided with the semicircular slit 5, of the shape and position adapted to fit the bail and bucket, substantially as specified.

In testimony whereof I have hereunto set my hand.

THEODORE F. W. SCHMIDT.
